US00D692431S

(12) **United States Design Patent**
Arceta

(10) **Patent No.:** **US D692,431 S**
(45) **Date of Patent:** **** Oct. 29, 2013**

(54) **BAR CODE SCANNER**

(71) Applicant: **Rubbermaid Commercial Products LLC**, Winchester, VA (US)

(72) Inventor: **Radmond Vincent Arceta**, Huntersville, NC (US)

(73) Assignee: **Rubbermaid Commercial Products LLC**, Winchester, VA (US)

(**) Term: **14 Years**

(21) Appl. No.: **29/449,454**

(22) Filed: **Mar. 15, 2013**

(51) LOC (9) Cl. **14-02**

(52) U.S. Cl.

USPC **D14/427**

(58) **Field of Classification Search**

USPC D14/420, 426-430, 453, 346, 341, 347, D14/412; D13/107, 184; 358/473; 235/462.43, 462.45, 462.47, 462.48, 235/462.44, 462.46, 487, 472.01, 472.02; 16/110.1, 430, 431; 439/133, 135; 709/219, 201; 710/73; 320/114, 115, 320/123; 361/679; 382/313, 321; 455/575.1, 561, 572

See application file for complete search history.

(57) **CLAIM**

The ornamental design for a "bar code scanner," as shown and described.

DESCRIPTION

FIG. 1 is a front perspective view of a bar code scanner, showing our new design;

FIG. 2 is a rear perspective view of the bar code scanner shown in FIG. 1;

FIG. 3 is a bottom perspective view of the bar code scanner shown in FIG. 1;

FIG. 4 is a top view of the bar code scanner shown in FIG. 1; FIG. 5 is a bottom view of the bar code scanner shown in FIG. 1;

FIG. 6 is a left side view of the bar code scanner shown in FIG. 1;

FIG. 7 is a right side view of the bar code scanner shown in FIG. 1;

FIG. 8 is a front view of the bar code scanner shown in FIG. 1; and,

FIG. 9 is a rear view of the bar code scanner shown in FIG. 1. Broken lines and portions contained within broken lines are not claimed.

1 Claim, 9 Drawing Sheets
